UNITED STATES PATENT OFFICE.

FRANK GILBERT HINSDALE, OF NEW YORK, N. Y.

MANUFACTURE OF CURTAINS.

Application filed January 12, 1923. Serial No. 612,176.

My invention relates to the manufacture of lace curtains, and has for its object to provide a novel and simple method of handling the curtains throughout the progress of manufacture from loom to kier, whereby objections and disadvantages heretofore existing are overcome and avoided. The invention contemplates further the provision of suitable apparatus of simple construction and operation, whereby the various steps in the novel method may be efficiently carried out. Other objects of the invention will appear from the description hereinafter and the features of novelty will be pointed out in the appended claims.

Reference is to be had to the accompanying drawings, which illustrate examples of the invention without defining its limits, and in which Figs. 1 and 2 illustrate the manner in which the lace leaves the loom; Fig. 3 illustrates diagrammatically the utility of the doffing machine; Figs. 4 and 5 illustrate schematically the arrangement whereby the measurement and inspection for defects in weaving of the lace fabric are carried out; Fig. 6 is a diagrammatic view illustrating the novel method of inspection and searching; Fig. 7 is a diagrammatic view illustrating the novel machine in use for piling curtains, and Fig. 8 is a diagrammatic view illustrating the method of plaiting the lace fabric into the kier for bleaching or other treatment therein.

To begin with, it may be stated that the essential feature of the present invention resides in the fact that the curtains may be handled as single sections, that is, single-width curtains, regardless of width throughout the various stages of manufacture subsequent to the weaving operation.

The curtains are woven in the usual manner lengthwise of the loom, there being, at times, as many as one hundred curtains located side by side in one piece of weaving; wherever the woven piece consists of two or more curtains they will, according to the present invention, be split apart into individual curtains directly on the loom after weaving and prior to being passed to the so-called batch-roll of the loom. That is to say, the piece of woven material *a*, Fig. 1, consisting of a plurality of individual curtains is passed over knives 20 located upon the breast-beam 21 of the loom in registry with the lines of division between adjacent curtain widths, or in a manner to split the

lace into individual curtains of any predetermined width. After having been split by the knives 20 into individual widths of curtains *a'*, Fig. 2, the latter are batched by being passed over suitably driven porcupine-rolls 22, and wound upon tubes 23, each of which is of suitable length to accommodate one curtain width and all of which are loosely mounted upon the batch-roll beam 24 of the loom, as shown diagrammatically in Fig. 2, means being provided to connect the tubes 23 to the beam 24, whereby the tubes may be positively driven when desired. As the next step, the curtains are doffed from the loom in the following manner: After the batch-roll beam 24 has been shifted to throw the rolls of curtains *a'* out of contact with the porcupine-rolls 22, the first width of curtain *a'*, for instance at the left-hand end of Fig. 2, is threaded around a tension bar 25, Fig. 3, and nipped between a doffing-machine roll 26 and a tube similar to 23, loosely mounted upon a spit-bar 27 (see Fig. 3), the tube normally lying in surface contact therewith. The doffing-machine roll 26 is then driven for instance at a speed of approximately two hundred yards per minute, which causes the lace from the first tube 23 to be rolled upon the spit-bar 27, which gradually moves away from the roll 26 in a predetermined path as the winding proceeds. As soon as the lace has been completely unwound from the first tube 23, the next width of curtain *a'* on the second tube 23 is similarly wound upon the bar 27 and added to the lace previously wound thereon. This operation is repeated until the loom is entirely doffed of lace, leaving one large roll *b* of lace commonly termed a section and consisting of the individual lengths taken from the plurality of small rolls previously on the loom. This large roll *b* of lace is then removed, as by being placed upon a conveyer and conveyed to the mending room, located, for instance, in another part of the mill, preferably the floor below the room in which the steps so far described have taken place. It will be understood that this suggestion of the location of the mending room need not be arbitrarily followed and represents merely an arrangement which has been found convenient and efficient.

It is necessary, in order to detect mistakes and inaccuracies in weaving and to insure the predetermined length in the cur-

tains, to measure the same which, in the present method, is accomplished by transferring the lace from the roll *b* to another roll *c*, Fig. 4, and coincidentally measuring the lace as it travels from one roll to the other; any mistakes in weaving due to lengths of the curtains in a given section will show itself identically in each section across the loom, so that it becomes necessary to measure but one individual section (as *a'* Fig. 2) to catch a mistake in the length of all curtains woven at the same time across the loom; the described step in the method may be carried out by passing the lace from the roll *b* over a suitable measuring roll 28 on to the roll *c*, combined counting and indicating means in the form of clocks 30 and 31, being operatively connected with the measuring roll 28 to maintain the count. To start measuring with the described arrangement the clocks 30 and 31 are set at zero, if said clocks are not already in this condition, the end of the first curtain being in registry with a suitable stationary indicator 29; the winding from one roll to the other is then carried on until the other end of the curtain is in registry with the indicator 29 whereupon the machine is stopped. The clock 30, which measures in inches or other predetermined units of measurement, is consulted and the total registered thereby noted and checked up with the order to see if the length is correct, it being obvious that the figures given represent the length of each curtain. The clock 30 is then rest to zero and the same operation is repeated with each curtain in a section until all curtains coming therefrom have been measured. The clock 31 is not reset, but will continue to operate and will serve to measure the total yards in the section and provide a check upon the individual curtains indicated on the clock 30. To check for accuracy the individual readings from the clock 30 may be totaled and compared with the grand total on the clock 31; if correct the totals will agree.

As the next step in the method, the curtains are inspected, this being done to check up the work of the weaver and to detect poor weaving, to sew together the ends of the different sections of lace in order to secure one continuous strand of single width curtains, to keep the latter intact as taken from the loom, and to maintain said curtains in a condition in which the gathering up of dirt thereby and damage resulting from careless handling are minimized. In carrying out this step of the method, the lace is passed from the roll *c*, Fig. 5, over a canvas screen 32 and wound up on a roll *d*. As the lace travels over the screen 32, which is used simply to provide a background which will quickly disclose imperfections in the lace, the latter is inspected for faults in weaving; such faults as may be discovered are called

to the attention of the weaver. As each section of lace runs from the roll *c*, its end is sewed to the end of the next succeeding section, for instance upon a sewing machine 33, which may be provided with a pin rail 34 on which the curtain ends are held while the machine sews the same together.

After the inspection of the curtains has been completed and all have been sewed together in a continuous length and wound up in a roll *d*, the lace is withdrawn from the latter over a canvas screen 35 (Fig. 6) and rolled up on a roll *e*. While the lace passes over the screen 35, which, like the screen 32, also serves as a contrasting background for the lace, a careful search is conducted for such imperfections as may exist therein; as each imperfection is found, the travel of the lace from the roll *d* to the roll *e* is temporarily suspended and said lace is mended to cure said imperfection, for instance by being drawn around a mending machine 36, whereby the mending is performed. After this has been done, winding of the lace from the roll *d* to the roll *e* is resumed until the next imperfection is reached, whereupon the same is mended, this operation being repeated as often as required until the lace has been completely transferred from the roll *d* to the roll *e*.

As the next step in the method, the lace is made up into kier lots, which means sewing together the lace while at its full width into a continuous strand sufficient to fill a kier, such strand being oftentimes as long as twenty-five thousand yards. This lace, is then folded back and forth, preferably by suitable mechanism comprising for instance a pot-eye 172 through which the lace, preferably in twisted, rope form, is passed, and a drum 136 and pressure roll 143 mounted upon a frame 131 and by the action of which the aforesaid lace is projected in a trajectory and thrown for a predetermined distance away from the machine. A vertically oscillated deflector 150 progressively varies the trajectory and causes the lace to be folded back and forth into the form of a pile *f*; after the latter has been completed, the lace is withdrawn therefrom and plaited into the kier 38, which may be of any customary form and construction. After the lot in the kier has been bleached or otherwise treated therein, the curtains are finished in any conventional manner.

Throughout the entire method, the curtains have been expeditiously handled with a minimum effort as single sections, and in a manner to reduce the possibility of overlooking inaccuracies and imperfections in the weaving to a minimum. The present method is much more efficient and reliable than existing methods and overcomes disadvantages therein some of which are recited hereinafter. At the present time curtains

are doffed at full width of loom or at width woven and are drawn by hand from the porcupine roll and placed upon a canvas on the floor of the mill. This is a very slow process. After complete doffing, the curtains, in the old method, are rolled up in the canvas and thrown to the mending room which is generally on the floor below; this obviously is a very crude method of handling the curtains and is likely to injure them and to excessively soil said curtains. The method of inspecting heretofore utilized is also crude and furthermore is costly and inefficient, many damaged pieces passing through the mending department with imperfections therein undiscovered by the inspection. In addition, with existing methods, the curtains being of large width are bulky to handle and when seams are sewn it prevents the opening of the material from the rope form to the open form by mechanical means. This is due to the width of the curtains and to the fact that it is necessary to fold over the seams three or more times in order to reduce the curtain to a width which may be readily handled. By handling the curtains in bundle form, as in existing methods, considerable space is taken up and damage is caused by dragging the curtains over floors, into aisles etc. and because they are walked upon and the like. Because of this unlimited amounts of dirt are picked up by the curtains which consequently become badly soiled. With existing methods the wide machinery which is required to dry and finish curtains of the said large widths can be operated only at low speeds and slowly which of course is expensive and adds to the cost of manufacture.

Various modifications in the sequence of the various steps of the method set forth and in the steps themselves may be made within the scope of the claims without departing from the nature of my invention.

I claim:

1. An improvement in the manufacture of lace which comprises weaving the lace upon a loom, dividing the lace into a plurality of individual strips of predetermined width as it leaves the loom, batching the strips by winding the same in the form of rolls, doffing the lace by withdrawing the strips from successive rolls and winding it in the form of a single roll, withdrawing the lace from said single roll and winding it in the form of another roll, measuring at least one of said strips in the passage of the lace between said rolls, searching the lace for defects as it passes from one roll to another, and forming the inspected lace in a pile to constitute a kier lot.

2. An improvement in the manufacture of lace material which comprises weaving the lace upon a loom, dividing the lace into a plurality of strips of predetermined width

as it leaves the loom, batching the strips by winding the same in the form of rolls on the batch roll beam, doffing the lace by withdrawing the strips from successive rolls and winding it upon a single roll, withdrawing the lace from said single roll and winding it into the form of another roll, measuring at least one of said strips in its passage between said rolls, searching the lace for defects as it passes from one roll to another, arresting the travel of the lace when a defect is found and mending the same, and forming the inspected and mended lace in a pile to constitute a kier lot.

3. An improvement in the manufacture of lace material which comprises weaving the material upon a loom, dividing the material into a plurality of individual strips of predetermined width as it leaves the loom, batching the individual strips by winding the same in the form of rolls, doffing the lace by withdrawing the strips from successive rolls and winding it in the form of a single roll, withdrawing the lace from said single roll and winding it in the form of another roll, searching the lace for defects as it passes from one roll to another, connecting the ends of said individual strips together to form a continuous strip, and forming said lace in a pile to constitute a kier lot.

4. An improvement in the manufacture of lace material which consists of weaving the material upon a loom, splitting the lace into a plurality of strips as it leaves the loom, batching the individual strips by winding the same in the form of a plurality of rolls, doffing the lace by withdrawing it from successive rolls and winding it into the form of a single roll, withdrawing the lace from said single roll and winding it in the form of another roll, measuring at least one of said strips as it passes from one roll to another, searching the lace for defects, securing the ends of the individual strips together to form a continuous strip, and forming the lace in a pile to constitute a kier lot.

5. An improvement in the manufacture of lace curtains which comprises weaving the curtains in a wide sheet on a loom, splitting the lace into individual curtain widths as it leaves the loom, batching the lace by winding the split widths in the form of rolls on tubes mounted on the batch roll beam of the loom, doffing the curtains by withdrawing the lace successively from the individual rolls and winding it in a single roll, withdrawing the lace from said single roll and winding it into the form of another roll, measuring and inspecting the lace in its passage from one roll to another, mending the defects found in the lace in the inspection operation, securing the ends of the individual curtain strips together, and forming the

inspected, measured, and mended lace in a pile to constitute a kier lot.

6. An improvement in the manufacture of lace curtains, which consists in batching individual curtain widths as they leave the loom by winding the curtain widths in the form of rolls upon tubes loosely fitted upon the batch-roll beam of a loom, doffing the curtains by withdrawing the lace from successive rolls and winding it into the form of a single roll, withdrawing the lace from said single roll and winding it into the form of another roll and causing the lace to operate measuring mechanism in its passage from one roll to another, withdrawing the lace from the last roll and passing it over a supporting screen to a succeeding roll, inspecting the lace as it passes over said screen for defects in weaving, withdrawing the lace from the roll last formed and passing it over a second supporting screen to another succeeding roll, searching the lace as it passes over said second screen for defects, arresting the travel of said lace when a defect is found and mending the same, withdrawing said lace from the last-mentioned roll and twisting it into rope form and folding it back and forth in a pile to constitute a kier lot, and plaiting said lace into a kier from said pile.

7. An improvement in the manufacture of lace curtains, which consists in weaving to-

gether a plurality of curtain widths, splitting the same apart into individual curtain widths upon the loom, batching the lace as it leaves the loom by winding the split widths into individual rolls upon individual tubes loosely fitted upon the batch-roll beam of the loom, doffing the curtains by withdrawing the lace successively from the individual rolls and winding it into a single roll, withdrawing the lace from said single roll and winding it into the form of another roll and causing the lace to operate measuring mechanism in its passage from one roll to another, withdrawing the lace from the last roll and passing it over a supporting screen to a succeeding roll, inspecting the lace as it passes over said screen for defects in weaving, withdrawing the lace from the roll last formed and passing it over a second supporting screen to another succeeding roll, searching the lace as it passes over said second screen for defects, arresting the travel of said lace when a defect is found and mending the same, withdrawing said lace from the last-mentioned roll and twisting it into rope form and folding it back and forth in a pile to constituted a kier lot, and plaiting said lace into a kier from said pile.

In testimony whereof I have hereunto set my hand.

FRANK GILBERT HINSDALE.
